SEAT BACK STRUCTURE

William F. Richardson and Raymond L. McQuitty,
Carthage, and Robert O. Isaacs, Joplin, Mo., assign-
ors to Flex-O-Lators, Inc., Carthage, Mo., a corpo-
ration of Missouri

Filed Aug. 5, 1963, Ser. No. 299,732

3 Claims. (Cl. 297—452)

This invention relates to new and useful improvements in seat back structures, and has particular reference to back structures used in upholstered furniture.

A principal object of the present invention is the provision of a novel backing or "decking" for the padding layers or "pillows" of a cushioned chair back which provides a resilient or springy base for the pillow, thereby contributing to greater comfort, and which also in and of itself provides adequate support for the pillow to prevent the padding from working between the individual wires of which the decking is formed. In most spring-supported upholstery, it is necessary to interpose a layer of fabric of one sort or another, usually called an insulator pad, between the springs and the padding layers in order to provide adequate support for the padding. The present structure utilizes such a fabric, but it is of such a nature, and is so suspended, that it serves both as a padding support, and also as a spring base.

Another object is the provision of a back structure of the character described having a novel structure permitting "localized" rather than "general" deflection when a load is applied thereto. That is, if a person presses one portion of his back, such as his hips or his shoulders, against the cushion with greater force than the other portions of his back, the position of the cushion against which he is pressing most forcibly will be free to yield freely with little or no yielding of other portions of the cushion. The cushion thus "contours" itself to the back of the user, and thus is conducive to greater comfort and less fatigue to the user.

Other objects are great simplicity and economy of structure in accomplishing functions which heretofore have required relatively complicated and expensive structures, efficiency and dependability of operation, and ease and economy of installation and construction.

With these objects in view, as well as other objects which will appear in the course of the specification, reference will be had to the accompanying drawing, wherein:

FIG. 1 is a front elevational view of a seat back structure embodying the present invention, with the padding layers omitted,

FIG. 2 is a sectional view taken on line II—II of FIG. 1, with the padding layers included,

FIG. 3 is an enlarged, fragmentary sectional view taken on line III—III of FIG. 1,

FIG. 4 is an enlarged, fragmentary sectional view taken on line IV—IV of FIG. 1, and

FIG. 5 is an enlarged, fragmentary sectional view taken on line V—V of FIG. 1.

Like reference numerals apply to similar parts throughout the several views, and the numeral 2 applies generally to the back frame of a furniture seat, said back frame being formed of wood or other suitable material and consisting of a pair of vertically extending side rails 4 rigidly connected at their upper ends by a horizontal cross bar 6 and adjacent their lower ends by a horizontal cross bar 8. The forward edges of side rails may, as shown, be shaped generally to the desired vertical contour of the back. The back frame may be affixed at its lower end to a seat frame 10, not pertinent to the present invention and shown only fragmentarily, including horizontal side rails 12 and a back rail 14.

2

The spring decking fabric is indicated generally at 16, and comprises a series of parallel, spaced apart and horizontally extending spring wires 18. Each of said wires is tightly looped or "knotted" at each end around a side cord 20 which is formed of twisted paper or other soft, indentable material, and which has a core consisting of a spring wire 22 (see FIGS. 3 and 5) which is of substantially greater diameter and stiffness than wires 18. Forming the side cord of paper or the like tends to prevent wearing of wires 22 with the padding layers which are eventually applied thereto as will presently be described, but most importantly they are indented by wires 18 as said wires are wrapped thereabout, and this serves to maintain said wires in properly spaced relation along the side cords. Intermediate cords 24, also formed of paper or the like, extend parallel to side cords 20, each of said intermediate cords being pierced by each of wires 18 at its point of intersection therewith, as best shown in FIG. 4. Said intermediate cords serve primarily to maintain proper spacing of wires 18 throughout their lengths, and the number and spacing of said cords will depend primarily on the width of the seat back to be fitted.

The spring decking fabric 16 extends over the back frame 2, the spacing between side cords 20 being somewhat less than the spacing between side rails 4 of said frame, so that each side cord is spaced somewhat inwardly from the adjacent side rail. Each side cord 20 is attached to the adjacent side rail by a series of spaced apart tension springs 26. Said springs are helical, and each spring is hooked at its inner end around the associated side cord 20 as indicated at 28 (see FIG. 5), and is hooked at its outer end around a nail 30 driven into the forward edge of the associated side rail 4, whereby to support fabric 16 resiliently.

FIG. 2 shows the padding or "pillow" 31 overlying the fabric 16. Said padding ordinarily has the surface thereof of adjacent fabric 16 covered with a protective textile fabric 32, and its outer or exposed surface covered with a protective and decorative fabric, leather or the like as indicated at 34. The fabric layers 32 and 34 are drawn rearwardly around the edges of the padding and secured to side rails 4, top cross bar 6 and bottom cross bar 8 in any suitable manner, such as by tacks 36.

It will be seen that decking fabric 16, supported by springs 24, provides a resiliently yieldable spring deck for the padding 31, which of course is conducive to greater comfort for the user than would be obtained if the padding were supported, for example, by the common jute webbing strips or the like. This yieldability is provided in part by the resiliency of wires 18 themselves, but principally by the springs 24. The stiffening of side cords 20 by their relatively stiff and heavy cores wires 22 provides a sufficiently solid and stable anchor for the inner ends of springs 24 that the fabric 16 will maintain its general contour over long periods of use and will not be distorted or pulled out of shape by said springs. The number and spacing of springs 24 may of course be varied as necessary or desired, although the spacing shown in FIG. 1 has been found entirely satisfactory in a standard upholstered chair back after extensive and exhaustive testing.

As fabric 16 is deflected rearwardly by a load applied to the cushion, the side cords 20 are drawn toward each other, as permitted by flexing of the core wires 22 in said side cords and the extension of springs 24. This deflection will of course be greatest where the load is greatest. For example, if a particular user tends to "slouch" in the chair so that his shoulders press heavily against the back, while his hips are positioned so far forward that they press against the back lightly if at all, the upper portion of fabric 16 will be relatively greatly deflected in a rearward direction, while the lower portion will be deflected only slightly if at all, and side cords 20 will assume a curved or

sinuous shape. Thus the structure shown permits the deflection of fabric 16 to be "localized" to a very large extent in the vertical zone of greatest load, leaving all other zones undeflected or only slightly deflected. This permits the back to assume the shape of the user's back regardless of the variations of posture he may assume. This may be termed a "contouring" effect, and is conducive to greater comfort and less fatigue to the user since his back is thereby more uniformly supported over its entire area.

The "localized deflection" and its resultant "contouring effect" provided by the present structure is of course not new in and of itself, existing in many presently available backs including a multiplicity of independently supported and individually deflectable spring units distributed uniformly over the area of the back. However, the provision of these effects in the extremely economical, easily and cheaply installed structure shown, by means of a simple fabric stretched over substantially the entire area of the back and secured only at its edges, is indeed believed to be novel, and forms the central feature of the present invention.

Wires 18 are of course not connected to each other, and are individually connected in spaced apart relation to side cords 20. This provides that when wires 18 in one zone of fabric 16 are deflected, and hence effectively shortened to draw side cords 20 in that zone closer together, said deflection will be transmitted to the adjacent zones of the fabric only to a very slight extent. This improves the localization of deflection which provides the desired contouring effect. If fabric 16 were continuous and inelastic, such as heavy canvas, so that vertically spaced portions thereof were not free to shift horizontally with respect to each other, the localization of deflection would be greatly lost, and loading one portion thereof would cause deflection in over a much greater vertical span thereof.

Also, wires 18 are spaced sufficiently closely together that they provide adequate support to prevent padding 31 from working rearwardly therebetween. In nearly all back structures, including springs, a wire-reinforced fabric, sometimes similar to fabric 16, must be laid over the springs to prevent the padding from working into the spaces within and between the springs. In the present structure, fabric 16 performs both the function of such an "insulator pad," and also the function of the springs themselves. This is of course a valuable economy.

While we have shown and described a specific embodiment of our invention, it will be readily apparent that many minor changes of structure and operation could be made without departing from the spirit of the invention as defined by the scope of the appended claims.

What we claim as new and desire to protect by Letters Patent is:

1. A seat back structure comprising:

- (a) a back frame including a pair of generally parallel, vertically extending side rails,

(b) a plurality of elongated tension springs attached to each of said side rails in vertically spaced relation therealong, and extending horizontally inwardly therefrom,

(c) a pair of vertically extending elongated resilient side strands attached respectively to the inner ends of each of the said tension springs of one of said side rails and

(d) a series of horizontally extending elongated resilient cross strands extending in parallel relation between said side strands and each affixed at its opposite ends to said side strands, said cross strands defining a deck over which padding may be applied.

2. A spring decking structure for use in furniture backs comprising:

- (a) a pair of generally parallel resilient side wires,
- (b) a plurality of generally parallel, spaced apart resilient cross wires extending between and affixed at their opposite ends to said side wires, and
- (c) means for supporting the structure formed by said side wires and cross wires in a furniture back frame with said side wires extending vertically and said cross wires extending horizontally, whereby said side wires are urged resiliently apart in a direction parallel to and in the plane of said cross wires.

3. A spring decking structure as recited in claim 2 wherein said supporting means comprises a series of elongated, resiliently extensible members each secured at one end to one of said side wires and extending outwardly

therefrom in the plane of the structure formed by said side and cross wires for attachment at its outer end to said furniture back frame, the space between the points of connection of successive resiliently extensible members to each of said side wires encompassing the points of connection of several of said cross wires to said side wire, and wherein each of said side wires is relatively stiff as compared to any one of said cross wires, whereby load stress applied to several of said cross wires is transferred by said side wires to one of said resiliently extensible members.
